UNITED STATES PATENT OFFICE.

HARRY M. McCASLIN, OF ELMIRA, NEW YORK, ASSIGNOR TO AMERICAN LA FRANCE FIRE ENGINE COMPANY, INC., OF ELMIRA, NEW YORK, A CORPORATION OF NEW YORK.

FIRE-EXTINGUISHER.

1,230,423.

Specification of Letters Patent. Patented June 19, 1917.

Application filed April 12, 1916. Serial No. 90,688.

To all whom it may concern:

Be it known that I, HARRY M. McCASLIN, a citizen of the United States, residing at Elmira, in the county of Chemung and State 5 of New York, have invented certain new and useful Improvements in Fire-Extinguishers, of which the following is a full and clear specification.

The present invention relates to improvements in fire extinguishers of the portable or hand type, in which a fire extinguishing fluid, such as carbon tetra chlorid, is carried in a suitable tank or container provided with a hand-operated pump, which causes the 10 fluid to be projected through the discharge nozzle of the container in a thin stream, which can be conveniently directed upon a fire.

This type of extinguisher is usually provided with means for maintaining communication between the discharge nozzle and the lowest part of the tank or container, whatever position the tank may be held in, said means being connected with the nozzle 15 either directly or through the pump, so as to permit the discharge of the entire contents of the tank or container in any desired direction.

In carrying out the invention of the present application I have mounted upon the fluid container of a portable fire extinguisher a double acting hand operated rotary pump, arranged between the container and the discharge nozzle, so as to effectively project a 20 stream of extinguishing liquid by a simple and continuous operation. An automatic valve controls the communication between the container and the pump, and means are provided for opening and closing said valve 25 by the operation of the hand lever, with the result that when the extinguisher is not in use the valve will be held in closed position and when placed in operation the simple act of rotating the operating crank will open 30 the valve for placing the pump in communication with the container. The rotary pump is reversible, so that it may be operated by rotating to either the right or left, according to the convenience of the operator. In reversing the action of the pump from right to left the controlling valve is automatically shifted for opening up communication between the container and the pump through proper channels to suit the reversal of operation. This reversal of the controlling valve

being automatic it will be understood in operating the extinguisher the operator can first rotate the pump in one direction and then, if tiring of that motion, can immediately reverse the direction of operation without concern as to the adjustment of any of the auxiliary parts. In addition to the automatic control of the valve referred to, suitable means are provided for locking the operative parts of the machine against motion when it is out of use.

In order that the invention may be fully understood I will first describe the same with reference to the accompanying drawings and afterward point out the novelty 70 more particularly in the annexed claims.

Figure 1 is a vertical longitudinal sectional view of a fire extinguisher having my improvements applied thereto;

Fig. 2 is a side elevation of the extinguisher head and pump removed from the container, the view being taken at right angle to that shown in Fig. 1;

Fig. 3 is a detail view of the operating crank with its retaining lock and means for 80 operating the controlling valve;

Fig. 4 is a detail sectional view of the valved air relief port with reversible controlling valve.

In the drawing, 1 is an extinguisher tank 85 or container designed to carry a suitable quantity of extinguishing liquid, such as carbon tetra chlorid. This tank 1 is formed with a cast head 2, fitted and secured upon the tank and carrying the pump mechanism 90 hereinafter referred to.

5 is the liquid discharging tube supported within the tank 1 parallel with its long axis and having its opposite ends 6 in open communication with the container adjacent 95 to its ends. 7 and 8 are valved disks mounted upon and connected by, a rod or wire 9 extending through the discharging tube 5 and so arranged that when one of said valved disks is in closed position the other 100 is held in open position. These connected valves 7 and 8 operate by gravity in a manner well understood in the art.

The discharging tube 5 is supported upon arms which are journaled in the longitudinal central axis of the container 1, so that tube 5 can rotate freely in the container and always take a position in the lowermost side of the container, no matter what position the extinguisher is held in. One of the support 110

arms of the tube 5 is a curved solid arm 12 embracing the tube 5 at one end and formed with a bearing stud 13 at its other end, which is freely journaled in the bearing 14 integral with or otherwise secured to the bottom end of the extinguisher tank 1. The support for the other end of the tube 5 is a tubular arm 16 embracing and secured to the end of the tube 5 at one end and formed with a tubular bearing stud 17, journaled in the bearing boss 18, projecting inwardly from the head 2. The tubular arm 16 is in open communication with tube 5 through the port 19 and with the discharging port 20 leading up centrally through the head 2 into the pump casing.

Formed integral with, or otherwise properly secured to the head 2, is a pump casing 25, embracing the two-part pump chamber 26, the discharge nozzle and the ports and passages leading to and from the pump chamber, as will now be described. 30 and 31 are the rotors of a double acting geared rotary pump, said rotors being mounted upon short shafts 32 and 33, which are suitably journaled in bearings 34, 35 of the casting 25 and 36, 37 of the removable face plate 38. The rotors 30 and 31 intermesh with each other and rotate within the usual segmental abutments 39 and 40, formed at opposite ends of the pump chamber 26.

The crank handle 50 is suitably secured to the shaft 32 of rotor 30, said crank 50 having a handle 51, pivoted in a bifurcated end of the crank, as indicated at 52, and formed with recesses 53, in its heel, for the engagement of latch 54, shown in the form of a ball mounted in the recess 50^a of crank 50, and engaged by the confined spiral spring 55, which holds the ball latch 54 in engagement with one of the notches 53 for retaining handle 51 in either operative or inoperative position. The operative position of the handle is at right angles to the main portion of the crank 50, as shown in full lines in Fig. 2. The inoperative position of the handle is shown in dotted lines in Fig. 2, in which position it is in line with and forms an extension of the main arm of crank 50 and rests between the integral lugs 56 upon the edge of head 2 for holding the parts against movement when the machine is not in use.

The discharging port 20 leading from the container passes into the circular valve chamber 60, from which the passageways 61 and 62 branch outwardly and communicate with ports 63, 64 upon opposite sides of the pump chamber 26 to act as inlet passages to said chamber. Seated in the valve chamber 60 is a valve plug 65 having the two-way ports 65^a 65^b, by which the discharging port 20 can be placed in communication with either of the passage ways 61 or 62, depending upon which direction the pump is operating.

65 70 and 71 are ports leading from the op-

posite sides of pump chamber 26 into the discharge passages 72 and 73 which converge and lead into the common valve chamber 74 which is in direct communication with the discharge nozzle 75. The plug 76 closes one side of the valve chamber 74 and is formed with a port 77 leading through it and completing the communication between passage way 73 and valve chamber 74. The inner end of the plug 76 is formed with a valve seat to receive the ball check valve 78. A similar ball check valve 79 is seated in the inner end of passageway 72, and compression spring 80 is arranged between the balls 78 and 79 to yieldingly hold them to their seats and allow one or the other to intermittently move off of its seat to permit the passage of liquid being discharged by the pump through the valve chamber into the nozzle.

In the formation of the intercommunicating passages and ports 61-63, 62-64, 70-72 and 71-73, above referred to, large recesses indicated at R are first drilled at the proper angles into the thickened side walls of the pump casing and the ports and passages referred to are then drilled from said recesses R to intercommunicate, as shown, through said recesses R. The outer ends of recesses R are then closed by plugs shown at P having flattened inner ends. The triangular representations in Fig. 1 are the inner conical ends of the recesses R.

Returning to the two-way controlling valve in the chamber 60 it will be observed that the conical valve plug 65 has a stop lug 65^a operating in a recess 65^b to determine the limits of the shifted positions of the valve. 65^a is a valve stem extending out from valve plug 65 toward the crank handle 50 of the rotary pump. Secured upon the end of this valve stem 65^a are two spaced leaf springs 85, 86 extending at a right angle to the axis of the valve 65 and of such length that they pass within the hub portion of crank 50 which is mounted upon the shaft 32. The outer ends of these leaf springs 85, 86 are curved slightly away from each other to form an expanded throat for the reception of the actuating pin which is carried by the crank, as will be presently explained. The springs 85 and 86 are faced and strengthened upon their outer faces by rigid metal strips 87, 88, the springs and strips being rigidly fastened in place upon the suitably shaped head or enlargement of the stem 65^a. 120 As shown in the drawing these parts are secured by bolts or rivets 89.

91 is an air relief passage leading through boss 92 into a chamber 93, communicating through port 94, with the interior of the container 1. This chamber 93 is an extension of valve chamber 60, above referred to, and the valve plug 65 extending through the chamber 93 is cut away as indicated at X, Y, Z, to permit a free com-

5 munication from air inlet port 91 into the container through port 94. One face of the valve plug, indicated at 65^e is adapted to close port 94 when the valve 65 is in its central closed position but permits communication through the port 94 when the valve is shifted to either of its operating positions. A ball check valve 95 prevents any outflow of liquid from the container through port 94.

10 The crank handle 50 carries an inwardly presented pin 100, which in the normal position of rest of the parts would be seated in the channel formed between spring members 85 and 86, as indicated in dotted lines in Fig. 3. In this position of the parts the two-way valve 65 is in its intermediate closed position, so that the passage way 20 is closed and the air inlet port 94 is also closed. When it is desired to use the extinguisher the operator holds the container in the most convenient position, releases the crank handle by moving the handle 51 outwardly into the position represented in full lines in Fig. 2 and immediately turns the 25 crank in the most convenient direction, with the result that the first turn of the crank will shift the valve 65 by reason of the engagement of pin 100 with springs 85, 86, thereby opening up the communication between the container and the pump chamber 26. The liquid is drawn from the container, forced out through the nozzle 75 in the desired direction and at every revolution of the crank 50, the pin 100 snaps past the 30 curved outer end of one of the springs 85 or 86. If it is desired to reverse the direction of operation of the pump, the operator simply turns the crank 50 in the reverse direction, with the result that at the first turn 35 the pin will enter the expanded throat between springs 85, 86, causing the valve plug 65 to be rocked into its reversed position for opening up communication between the container and the reverse side of the rotary 40 pump.

45 I claim:

1. In an extinguisher, the combination of 50 a fluid container, a pump casing, a reversible rotary pump operating in said casing, means communicating between said pump casing and the container, a discharge nozzle and valved passage ways leading from opposite sides of said casing to said discharge nozzle.

55 2. In an extinguisher, the combination of a liquid container, a discharge nozzle, a reversible rotary pump arranged between said container and said discharge nozzle, valved discharge passage ways leading from opposite sides of said pump to said nozzle, means 60 communicating between opposite sides of said pump and the container, a valve controlling the communications between the pump and container and pump operating means adapted to operate said valve.

3. In an extinguisher, the combination of a liquid container, a discharge nozzle, a rotary pump forming communication between the container and discharge nozzle, means for operating said pump and a valve opened and closed by said pump operating means and controlling the communication between the pump and container. 70

4. In an extinguisher, the combination of a liquid container, a discharge nozzle, a reversible rotary pump arranged between the container and discharge nozzle, inlet and outlet passage ways leading into and out of opposite sides of the pump, means for operating said pump, a valve controlling the inlet passage ways between the pump and container and having two open positions, pump operating means, and means actuated by said operating means adapted to move said valve into its closed or its two open positions. 75

5. In an extinguisher, the combination of a liquid container, a discharge nozzle, a reversible rotary pump having two-way communication with the container, a reversible valve controlling said two-way communication between the container and pump, a valve between the pump and nozzle and means actuated by the reversal of said pump for operating said reversible valve. 80

6. In an extinguisher, the combination of a liquid container, a reversible rotary pump having a discharge nozzle, passageways communicating between the pump and the container, a two-way reversible valve controlling the passageways between the container and pump, a pump operating crank, and means actuated by the reversal of said crank for operating said valve. 95

7. In an extinguisher, the combination of a liquid container, a pump chamber, a discharge nozzle, a reversible rotary pump in said chamber, valved passage ways leading from opposite sides of said chamber to said nozzle, passageways leading from said container to the opposite sides of said chamber, 100 a two-way valve controlling said container passageways. 105

8. In an extinguisher, the combination of a liquid container, a pump casing communicating with said container, a discharge nozzle leading from said pump casing, a rotary pump operating in said casing, a crank for operating said pump, a valve controlling the communication between the container and pump casing, and operating 115 means between the crank and valve. 120

9. In an extinguisher, the combination of a liquid container, a pump casing communicating with said container, a discharge nozzle leading respectively from said pump casing, a rotary pump operating in said casing, a crank for operating said pump, a rotary valve, between the pump casing and container, operating upon an axis approximately parallel to the axis of rotation of 125 130

said crank, an arm projecting from said valve approximately parallel with said crank, and a pin carried by said crank adapted to engage said valve arm.

- 5 10. In an extinguisher, the combination of a liquid container, a pump casing communicating with said container, a discharge nozzle leading from said pump casing, a rotary pump operating in said casing, a crank for operating said pump, a valve between the pump casing and container, a spring arm mounted upon said valve, and a pin or lug carried by said crank and adapted to engage said spring arm for operating said valve.
- 10 15. 11. In an extinguisher, the combination of a liquid container, a pump casing communicating with said container, a discharge nozzle leading from said pump casing, a rotary pump operating in said casing, a crank for operating said pump, a valve between said pump casing and container, a pair of spaced spring arms mounted upon said valve and projecting approximately parallel to said crank, and a pin carried by said crank adapted to rest between said spring arms for holding the valve in closed position and for turning the valve in either direction, de-

pending upon the direction of rotation of the crank.

12. In an extinguisher, the combination 30 of a liquid container, a pump casing communicating with said container, a discharge nozzle leading from said pump casing, a rotary pump operating in said casing, a crank for operating said pump, a valve arranged 35 between the pump casing and container, a pair of spaced spring arms secured upon said valve and formed with oppositely curved outer ends, said spring arms being located approximately parallel to said crank, 40 and a pin carried by said crank adapted to engage said spring arms for operating said valve.

13. In an extinguisher, the combination 45 of a liquid container having an air vent inlet, a pump casing communicating with said container, a discharge nozzle for said pump casing, a rotary pump operating in said casing, a crank for operating said pump, a rotary valve controlling the communication between the casing and container and the vent opening into the container, and operating means between the crank and valve.

HARRY M. McCASLIN.
